[57] ABSTRACT

An apparatus that receives ambient sounds and recognizes the occurrence of coughs to the exclusion of other sounds. Means are provided for translating the received sounds into a plurality of spectral component signals. A feature signal generating means is provided for sensing the presence of properties of the spectral component signals that are characteristic of coughs and for generating a feature signal for each property found to be present. An occurrence decision means, responsive to the feature signals, generates an occurrence indication upon receiving a predetermined combination of feature signals. In a preferred embodiment of the invention, the occurrence decision means is programmable to the cough of a particular individual.

COUGH MONITORING APPARATUS

BACKGROUND OF THE INVENTION

This invention relates to apparatus for recognizing the occurrence of specified non-verbal sounds, and, more particularly, to apparatus for automatically recognizing and counting the occurrence of coughs.

There are various situations in which it is desirable to monitor the rate at which a human subject coughs. The information can be useful in evaluating the effectiveness of a medication or in determining the condition of the patient. When the patient himself or a third party is assigned the monitoring task there are obvious disadvantages of inconvenience, cost and unreliability.

Equipments that attempt to automatically monitor human cough rates have been previously developed, but are found to suffer various deficiencies. As an example, one prior art device includes a pneumatic band that is fitted around a patient's chest and connected to a recorder through pneumatic tubes. Problems of patient discomfort limit this device's usefulness. Another scheme provides a microphone carried on a patient's person or positioned nearby. Sounds received by the microphone are transmitted as electrical signals to a receiver which triggers a counter whenever the power of the received signals exceeds a predetermined level. The drawback of this system is triggering by sounds other than the coughs of the patient being monitored. Conversation and other room noises can cause such extraneous triggering with a resultant incorrect cough count.

In view of the disadvantages of prior art systems, it is an object of the present invention to provide an improved apparatus which detects coughs with reliability and without patient discomfort.

SUMMARY OF THE INVENTION

The present invention is directed to an apparatus which receives ambient sounds and reliably recognizes the occurrence of specified non-verbal sounds, e.g., coughs, to the exclusion of other sounds. Means are provided for translating the received sounds into a plurality of spectral component signals. A feature signal generating means is provided for sensing the presence of properties of the spectral component signals that are characteristic of coughs and for generating a feature signal for each property found to be present. An occurrence decision means, responsive to the feature signals, generates an occurrence indication upon receiving a predetermined combination of feature signals.

In a preferred embodiment of the invention, the occurrence decision means is programmable for different specified sounds, for example, the cough of a particular individual.

Further features and advantages of the invention will become more readily apparent from the following detailed description when taken in conjunction with the accompanying drawings.

DESCRIPTION OF THE DRAWINGS

FIG. 1 is a graphical representation of the general shape of the energy vs. frequency spectrum for a typical human cough;

FIG. 2 is a block diagram of an embodiment of a cough monitoring apparatus in accordance with the invention;

FIG. 3 is a block diagram of the translating means portion of the invented apparatus;

FIG. 4 is a block diagram representation that illustrates the functioning of the feature signal generator utilized in the present invention;

FIG. 5 is a block diagram of the storage means and occurrence decision logic means utilized in the present invention.

FIG. 6 is a side perspective view of a console utilized to house an embodiment of the present invention.

FIG. 7 is a block diagram of the duration sensor utilized in the occurrence decision logic means of FIG. 5.

DESCRIPTION OF THE PREFERRED EMBODIMENTS

Referring to FIG. 1, there is shown an energy vs. frequency plot that illustrates the typical instantaneous shape of a human cough. The arrows at F_1 through F_{15} represent the energy levels at selected frequencies of a cough and the dashed line represents the spectrum envelope.

It has been found that coughs have certain combinations of distinguishing characteristics that are usually not present in speech or ambient room noise. Generally, a cough is noiselike burst of energy of substantial duration characterized by a sharp onset and having a single broad peak in its energy vs. frequency spectrum as shown in FIG. 1. The frequency components that contain most of the cough energy are in the range about 500-7500 c.p.s., and the broad peak is typically in the range about 1,000-3,000 c.p.s. Many speech sounds, on the other hand, have two or more distinct peaks or "formants" in their energy vs. frequency. Also, it has been empirically determined that certain slope and energy relationships exist between the different spectral components of most coughs. By determining which of a judiciously selected set of relationships or features is present in the cough of a particular individual, and then programming the invented apparatus to sense the presence of the determined combination, it is possible to achieve recognition accuracies that were heretofore unattainable.

Referring now to FIG. 2, there is shown a block diagram of an embodiment of a cough recognition system in accordance with the invention. A transducer 30, typically a gradient microphone, receives ambient input sounds and produces time-varying electrical signals representative of the received sounds. (Hereinafter, the phrases "input sounds" or "ambient input sounds" are generically defined as including sound-representative signals, for example, signals from a tape recorder that were taken at a patient's bedside for later processing.) The sound representative signals are coupled over a line 30a to a translating means 20 that includes, inter alia, a bank of frequency-selective devices such as bandpass filters. The output of the translating means is a plurality of signals on lines 20a through 20p. These output signals represent spectral components of the received sounds and can be pictured, for example, as reflecting the energy levels at the selected frequencies shown in FIG. 1.

A feature signal generating means 50 receives the spectral component signals 20a through 20p and senses the presence of properties of the spectral component signals that correspond to preselected properties or "features" of coughs. The manner in which this is

achieved is described in further detail hereinbelow. It suffices for the present to understand that each of the output lines corresponds to one of the preselected features, and an output on any one of these lines indicates the presence of the corresponding preselected feature in the input sounds.

The feature signal lines are coupled to both a storage means 100 and occurrence decision logic means 150. Storage means 100 is utilized, in conjunction with display means 105, during a training phase of the apparatus operation to obtain a lasting display of the features present in a sample cough of a particular individual. Assisted by the display, a human operator can manually program the decision logic 150 to recognize the coughs of the individual that supplied the sample and record the number of such coughs in a counter 155. By programming the decision logic to the cough of an individual, it is possible to obtain high recognition accuracies. Also, the manual programming technique does not require unduly expensive circuitry.

The translating means 20 is shown in further detail in FIG. 3 and is seen to include a preamplifier 21 the output of which provides parallel inputs into a bank 22 of fifteen contiguous bandpass filters, f_1 through f_{15} . Each of the band-pass filters in the bank 22 receives the preamplified input signal and produces an output signal related to that portion of the input signal which lies in the range of frequencies passed by the particular filter. In the present embodiment, the filter center frequencies range from about 700 c.p.s. to about 6,500 c.p.s. with the lowest filter bandwidth being about 300 cycles. The present embodiment is thus designed without particular sensitivity to frequencies below about 500 c.p.s. These lower frequencies can be quite useful in determining the presence of certain speech sounds, but it is found that coughs are not rich in the frequencies at the lower end of the speech spectrum, so an economy of filters can be implemented herein.

The output of each filter in the bank 22 is individually coupled to a full wave rectifier and lowpass filter combination located in a rectifier/filter bank 23. After rectification and filtering, the outputs of the bank 23 essentially represent the energy levels of the input signal at about the center frequencies of each of the band-pass filters in the bank 22. Viewed in another way, the signals on lines 23a through 23p collectively represent the envelope of the energy vs. frequency of the received input signal taken over the frequency range of interest.

The fifteen channels of information on lines 23a through 23p are logarithmically compressed to produce the spectral component outputs on lines 20a through 20p of the translating means 20. Logarithmic compression facilitates subsequent processing in two ways. First, it provides dynamic range compression that simplifies the engineering design requirements of feature signal generator 50. Secondly, by virtue of using logarithms, comparative ratios of the spectral component signals can be readily computed by subtraction. Ratios are desirable processing vehicles in that they are independent of changes in overall signal amplitudes. This property is particularly advantageous in a cough detection system where coughs of varying intensity are to be monitored.

In the diagram of FIG. 3, a single log amplifier 25 is time shared to avoid the necessity of using fifteen identical amplifiers to achieve compression. The outputs on

lines 23a through 23p are effectively sampled by a multiplexer 24 and the sampled signals passed, one at a time, through the shared amplifier 25. A demultiplexer 26 then "reconstructs" compressed spectral component signals on lines 20a through 20p from the processed sampled signals. The sampling clock rate of the multiplexer and demultiplexer is above one megacycle and is safely higher than is necessary to retain signal bandwidths. This technique of sharing a single logarithmic amplifier is known in the art and is disclosed, for example, in U.S. Pat. No. 3,588,363 of M. Herscher and T. Martin entitled "Word Recognition System for Voice Controller."

Referring again, momentarily, to FIG. 2, it will be recalled that the spectral component signals on lines 20a through 20p are entered into the feature signal generator 50 which senses the presence of properties of the spectral component signals that correspond to preselected properties or "features" of coughs. In the present embodiment, this sensing of properties or "feature extraction" is achieved in part by deriving quantities known as positive and negative broad slope characteristics. These quantities give indication as to the polarity and magnitude of the slope of the input envelope (e.g., FIG. 1) when taken over specified relatively broad segments of frequency spectrum.

The manner in which broad positive slopes and broad negative slopes are obtained is described in detail in the above-referenced U.S. Patent of Herscher and Martin. 30 A broad positive slope at a particular frequency reference point is defined by the equation

$$BPS_n = K[(E_{n+1} + E_{n+2}) - (E_n + E_{n-1})]$$

where K is a gain constant, the E 's refer to the amplitudes of the processed spectral component signals on lines 20a through 20p, and n is a reference index that corresponds to the subscript index of the filters in the bank 22. For example, the broad positive slope at the reference frequency F_5 (FIG. 1) is computed as

$$BPS_5 = K[E_6 + E_7] - (E_5 + E_4)]$$

A BPS has a non-zero value only when positive; i.e., when the first parenthetical term, $(E_{n+1} + E_{n+2})$, is greater than the second parenthetical term, $(E_n + E_{n-1})$. Otherwise, the BPS is zero.

The broad negative slopes are defined by

$$BNS_n = K[(E_n + E_{n-1}) - (E_{n+1} + E_{n+2})]$$

and similarly have non-zero values only when positive. 50 The physical implementation of the equations for the broad positive slopes and broad negative slopes is accomplished by using operational amplifiers. These units, when fitted with appropriate peripheral circuit components, provide analog output signals which are proportional to the difference between the sum of the amplitudes of signals at "excitory" input terminals and the sum of the amplitudes of signals at "inhibitory" terminals. With 15 spectral component signals, E_1 through E_{15} , there are 14 possible broad positive slopes from BPS_1 to BPS_{14} and 14 corresponding broad negative slopes from BNS_1 to BNS_{14} . (Calculations of BPS_{15} and BNS_{15} reduce to zero and $K(E_{15} + E_{14})$, respectively, and therefore provide no meaningful slope information.)

65 Referring to FIG. 4, there is shown a block diagram of the feature signal generator 50. The spectral component signals on lines 20a through 20p are received from

the translating means 20 (FIG. 2) and coupled to a broad slope generator 51 that functions to develop BPS and BNS signals in the manner described above. The bracket 52 encloses the signals available for further processing; i.e., the spectral component signals E_1 through E_{15} , the broad positive slope signals BPS₁ through BPS₁₄, and the broad negative slope signals BNS₁ through BNS₁₄. For clarity of illustration, the interconnection of these signals to subsequent circuitry is not shown, it being understood that they are each available as inputs.

An operational amplifier 52 receives as "excitory" inputs the signals BNS₁₁, BNS₁₂, BNS₁₃ and BNS₁₄, and receives as "inhibitory" inputs the signals BNS₂, BNS₃, BNS₄ and BNS₅. In the manner previously described, the amplifier 52 provides an analog output that is proportional to the amount by which the sum of the amplitudes of the signals at the excitatory inputs exceed the sum of the amplitudes of the signals at the inhibitory inputs. Again, if the inhibitory input sum is greater than the excitatory input sum, the amplifier output is zero. The amplifier 52 thus produces an output only when selected broad negative slopes at the higher end of the considered frequency spectrum are collectively greater than selected broad negative slopes at the lower end of the considered frequency spectrum. The property being detected, i.e., a general negative slope or "roll-off" at the higher end of the considered spectrum, has been found to be a common cough characteristic or feature. Receiving the output of amplifier 52 is a NAND gate 52 which, absent an input of predetermined threshold from amplifier 52, produces a logical "1" output. When the output of amplifier 52 exceeds a predetermined threshold level, the gate 53 produces a logical "0" on its output line 53a, an occurrence that is designated as a "Feature 5" signal.

The amplifier 54 and gate 55 similarly act to produce a "Feature 6" signal on line 55a when another selected portion of the high frequency rolloff (BNS₈ through BNS₁₁) exceeds any existent rolloff at another portion of low frequency spectrum (BNS₂ through BNS₅).

The amplifier 56 compares spectral component relative energies, producing an output proportional to the amount by which the sum of E_6 , E_7 , and E_8 exceeds the sum of E_{13} , E_{14} , and E_{15} . When the output of amplifier 56 is above a predetermined threshold level, the gate 57 produces a logical "0" that is designated as a "Feature 7" signal on line 57a. Feature 7 is, again, a measure of a determined cough characteristic, i.e., a particular energy ratio at the lower end of the considered frequency spectrum.

The remainder of the amplifiers 58, 60, 62, 64 . . . 70, and corresponding gates 59, 61, 63, 65 . . . 71, receive spectral component signals or broad slope signals and can produce signals on lines 59a, 61a, 63a . . . 71a, that are indicative of Features 8 through 14. Features 8, 9, and 11, for example, detect the presence of the relatively broad peak of energy at about the middle of the considered spectrum, a characteristic found present in most coughs. Features 10 and 14 detect the presence of particular broad slope characteristics of interest.

In addition to Features 5 through 14, the feature generator 50 generates a group of features signals that are subsequently used in a special manner in the present embodiment. These "special" features are designated herein as Feature 1 through Feature 4. The Features 2 through 4 detect the same characteristics detected by

the Features 5 through 10, but in a less restrictive manner. For example, the outputs of NAND gates 53 and 55 are coupled to the inputs of an AND gate 72. When either of the signals on lines 53a or 55a is a logical "0," the output of gate 72 is also a logical "0." Thus, a logical "0" signal on output line 72a, designated as Feature 2, will occur when either Feature 5 or Feature 6 is present. The same relationship exists as between Feature 3 (the output of gate 73 on line 73a) with Features 7 and 10, 8, and as between Feature 4 (the output of gate 74 on line 74a) with Features 9 and 10. In other words, Feature 3 will be present whenever either Feature 7 or Feature 8 is present, and Feature 4 will be present whenever either Feature 9 or Feature 10 is present.

The remaining "special" feature is Feature 1, which is present when the sum of spectral component signals E_2 through E_{13} exceeds a predetermined threshold. (Recalling that we are dealing with logs, a product of energies is actually represented.) This feature detects 15 the broad spread of substantial energy that is characteristic of coughs. The inputs E_2 through E_{13} are received by operational amplifier 75 which produces an output when the sum of the inputs exceeds a predetermined threshold level. This output is fed to NAND gate 76 which produces a logical "0" on its output line 76a, designated a "Feature 1" signal, when the threshold condition is met.

Referring to FIG. 5, there are shown block diagrams of the storage means 100, the display means 105, and the occurrence decision logic 150. The lines carrying the signals that represent Feature 1 through Feature 4 are received by flip-flops 111 through 114 in storage means 100. These flip-flops, which initially have a "low" output level by virtue of a manual reset signal on a line 106, are of the type that are set to a "high" output by an input transition from a logic "1" to a logical "0." The signals that represent Feature 5 through Feature 14 are coupled, via OR gates 125 through 134, to another group of the same type flip-flops, 115 through 124. The other input to each of the OR gates 125 through 134 is an "enable" signal received over a common line 136. The signal on line 136 is normally at a logical "1" level so that the outputs of the OR gates 125 through 134 are maintained at "1" and the flip-flops 115 through 124 are inhibited from being set to a "high" output state.

The outputs of the flip-flops 111 through 124 are coupled to lamp drivers D₁ through D₁₄ in display means 105 which, in turn, activate the respective lamps L₁ through L₁₄. The lamps L, numbered by the features to which they correspond, can be conveniently displayed on the faceplate of a console 300 that houses the system electronics, as is depicted in FIG. 6.

Referring again to FIG. 5, the lines carrying signals representative of the 15 features are also received by the occurrence decision logic 150 wherein they are each coupled to one of a group of toggle switches S₁ through S₁₄. The other ends of the 15 switches are received as input lines to a NOR gate 155, the output of which is coupled to an adjustable duration sensor 160. The duration sensor, described in further detail below, produces an output only after receiving an input of a specified minimum duration. The lines from switches S₁ through S₄ are also coupled as inputs to another NOR gate 165, the output of which is fed to an "enable" generator 170 that preferably comprises a one-shot multivibrator. The output of the enable generator 170 is in-

verted by NAND gate 175 to become the enable signal on line 136. The toggle switches, designated by the features to which they correspond, are mounted on the faceplate of console 300 (FIG. 6), adjacent their correspondingly numbered lamps. Also, the manual reset line 106 is coupled to a logic level "1" supply (not shown) through a pushbutton switch on the console 300.

The operation of the system typically commences by programming or "training" the apparatus to the cough of a particular individual. First, an operator puts all switches S₁ through S₁₄ in the closed (down) position. The reset button on the console is then pressed and the resultant signal on line 106 (FIG. 5) resets all the flip-flops 111 through 124 so that the lamps L₁ through L₁₄ are all off. At this point, assuming for the moment that ambient room noise is zero, the signals which represent Feature 1 through Feature 14 (FIGS. 4 and 5) are all at a logic "1" level and, consequently, the outputs of the NOR gate 155 and 165 are at a logic "0." Thus, the output of the enable generator 170 is at "0" so that the output of inverter 175 is at "1," effectively disabling flip-flops 115 through 124 by action of line 136.

A sample cough of a patient, taken either live or from a recording, is next entered into the translating means, for example, via transducer 30. Assume for the moment that the input cough contains characteristics that activate Feature 1 through Feature 4 (which is likely) in addition to certain other Features, say 5, 7, 9, 10, 11, 13 and 14. If this occurs, the signals corresponding to these features change to a logic "0" and, as one consequence, the four inputs to NOR gate 165 are at "0" so the output of NOR gate 165 goes to "1." This results in the enable generator producing a "1" output for a predetermined duration (preferably about 1 second) so that a "0" enable signal appears on line 136 for about 1 second. The OR gates 125 through 134 are thus enabled to pass the "0" levels of the activated features among Feature 5 through 14 to set the corresponding flip-flops among flip-flops 115 through 124. Also, the flip-flops 111 through 114 are set by the transitions to "0" of the signals representative of Feature 1 through Feature 4. As a result, all lamps corresponding to the occurring features are lit and stay lit. (It should be noted at this point that the sample cough does not activate NOR gate 155 since, with all switches closed, some of the inputs to the gate are at a logic "1" level; i.e., the inputs corresponding to Features 6, 8, and 12 for the example given.)

The operator observes which lamps are not lit and opens the switches S that correspond to the unlit lamps. The apparatus is then programmed for the cough of the individual that supplied the sample cough. To illustrate, if, in the example given, the switches S₆, S₈, and S₁₂ are opened during programming, a subsequent cough by the patient that contains the Features 1 through 5, 7, 9, 11, 13 and 14 will cause a "1" output from NOR gate 155 since this gate will now have no inputs at the logic "1" level. If the output of NOR gate 155 lasts for longer than the predetermined duration of sensor 160 (i.e., if all the inputs 1 through 5, 7, 9, 10, 11, 13 and 14 last for this predetermined duration), the sensor 160 will produce an output that trips the counter 190 (FIG. 2).

From the above description it is seen that the absence of an enable signal on line 136 prevents the lamps L₅ through L₁₄ from being individually lit by extraneous

ambient noise that occurs during the programming phase of operation. It is only when Features 1 through 4 occur simultaneously (and this is highly unlikely except during a cough) that the lamps L₅ through L₁₄ can be lit. Thus, the probability of an improper programming is minimized.

There is the possibility that the coughs of certain individuals will not contain all of the Features 1 through 4. If this occurs, when the training sample cough is received only some of the lamps L₁ through L₄ will be lit, say, L₁ through L₃. In such event, the operator can open switch S₄, effectively introducing a logic "0" input on the Feature 4 input line to NOR gate 165. Now, the enable signal on line 136 can be triggered by the occurrence of Features 1 through 3, so the operator can press the manual reset button and receive another training cough to accomplish a proper programming.

Variations in the programming procedure can be implemented to further reduce the probability of extraneous triggering of the counter or to increase the sensitivity of the apparatus. For example, a number of training coughs can be received during the programming phase (normally resetting the lamps after each one) and the switches S opened for any feature that does not occur during every training cough. Another technique for modifying the sensitivity of the apparatus to a desired level is adjustment of the duration sensor critical time. This is conveniently accomplished during the programming phase by a trial and error technique of determining the maximum setting at which a patient's cough trips the counter.

Referring to FIG. 7, there is shown a simplified block diagram of the duration sensor 160. The output of NOR gate 155 is received by an adjustable one-shot multivibrator 161 that is preferably adjustable to remain in its unstable state for between about 50 ms. to 250 ms. from its last triggering. The one-shot 161 is of the type that has an output that is normally "high" (a logical "1") until triggered by the edge of a positive-going signal whereupon its output goes to a logical "0" level. The output of one-shot 161 is received by AND gate 162. The output of NOR gate 155 is also coupled, via a short delay means 163, to AND gate 162. The delay means 163 need only provide a delay which is longer than the propagation time of the one-shot 161 and may have, for example, an intrinsic delay of about 100 nanoseconds. Another one-shot 164, which is of the same type as one-shot 161 but has a longer and fixed unstable state of about 1 second, receives the output of AND gate 162. The output of one-shot 164 is fed back as an input (designated 164a) to AND gate 162 and is also received by the counter 190 (FIG. 2) which is of the type that is triggered by the edge of a negative going signal.

The operation of duration sensor circuit 160 is as follows: Assume that the adjustable one-shot 161 is set at a 250 ms. duration. When the output of NOR gate 155 (designated 155a) is "0" the AND gate 162 is disabled by its center input (designated 163a). When 155a goes to "1," the output of one-shot 161 (designated 161a) goes to "0" and remains there for 250 ms. The delay 163 prevents 163a from being at "1" until after 161a has gone to "0" so that both these signals can't be at "1" simultaneously at the onset of a "1" on line 155a. After 250 ms. have elapsed from the time that 155a went to "1," the one-shot 161 will return to its stable output of "1." If 155a has remained at "1" during this

250 ms., the three inputs to gate 162 will be at "1" simultaneously and the resultant output of gate 162 will trigger one-shot 164 to a "0" state which, in turn, trips the counter. The fed-back "0" on line 164a then prevents the one-shot 164a from triggering again for at least 1 second so that no more than one cough per second can be counted. Also, it should be noted that, in order to trigger the one-shot 164, the input 155a must be at "1" continually for the specified time of 250 ms. If 155a returns to "0" and then goes back to "1" during a given 250 ms. interval, the one-shot 161 will start a new 250 ms. "counting" period from the latest excursion to "1."

As above-stated, the duration sensor 160 (FIG. 5) can be adjusted to the maximum setting at which a patient's cough is found to trip the counter. By so doing, the probability of the counter being triggered by extraneous noise is reduced even further. The preferred procedure is to start at a setting of 250 ms. and, after programming, observe whether sample coughs trip the counter. If not, successively shorter settings can be tried until appropriate results are obtained.

While the invention has been described above with reference to a particular embodiment, it will be appreciated that variations are available within the spirit of the invention. As an example, the duration sensor 160 may be designed to produce an output for a less restrictive condition that requires an input only at the beginning and end of a specified period rather than continuously during such period.

We claim:

1. Apparatus for receiving ambient input sounds and recognizing the occurrence of coughs to the exclusion of other sounds, comprising:

- a. means for translating said input sounds into a plurality of spectral component signals;
- b. feature signal generating means for sensing the properties of a single broad peak of energy in the spectral component signals and for generating a feature signal for each such property found to be present; and
- c. occurrence decision means responsive to said feature signals for generating occurrence indications upon receiving a predetermined combination of said feature signals, irrespective of the order of arrival of said feature signals.

2. Apparatus as defined in claim 1 wherein said feature signal generating means includes means for sensing a predetermined minimum energy product in the spectral component signals.

3. Apparatus as defined by claim 1 further comprising duration sensing means which enables occurrence indications only when the predetermined combination of feature signals is continuously present for a predetermined duration.

4. Apparatus as defined in claim 1 wherein said occurrence decision means includes a plurality of manually operable switches and a gate, each of said switches coupling a feature signal to said gate, the presence of a feature signal on all gate inputs that are coupled through closed switches causing activation of said gate.

5. Apparatus as defined by claim 4 wherein said occurrence decision means further includes duration sensing means which allow occurrence indications when said gate is continuously activated for a predetermined duration.
